CLAIM

The ornamental design for a floodlight, as shown and described.

DESCRIPTION

FIG. 1 is a front, left side, perspective view of a floodlight with hinged side attached at left side of the floodlight;
FIG. 2 is a front elevation view thereof;
FIG. 3 is a rear elevation view thereof;
FIG. 4 is a right side elevational view thereof;
FIG. 5 is a left side elevational view thereof;
FIG. 6 is a top plan view thereof;
FIG. 7 is a bottom plan view thereof;
FIG. 8 is a front, left side, perspective view of a floodlight with hinged side attached at right side of the floodlight and opened at 90 degrees;
FIG. 9 is a front elevation view of the floodlight with hinged side attached at left side of the floodlight and opened at 90 degrees; and,
FIG. 10 is a front elevation view of the floodlight with hinged side attached at right side of the floodlight and opened at 90 degrees.
The dotted lines illustrate environmental structure or portions of the floodlight that form no part of the claimed design.
